Application January 3, 1934, Serial No. 705,129
In Germany June 1, 1932

2 Claims. (Cl. 131—52)

My invention relates to cigarettes the wrappers of which do not consist of paper but of tobacco.

The primary object of my invention consists 3 in a cigarette with a tobacco wrapper which is stable, elastic and able to offer resistance to destructive forces. Other objects of my invention will become apparent from the following specification of my improved manufacturing method.

10 According to my invention the filling of the cigarette is wrapped with threads of tobacco which are spun from cut tobacco, and such threads may be wrapped directly about the filling, or a fabric woven from the said tobacco threads

15 may be used as wrapper of the cigarette.

In carrying out my improved method the tobacco leaves are longitudinally cut to long strips of very small breadth which are spun to threads like textile fibres. On account of the small tensile strength of the tobacco threads, the spinning is performed by well-known mechanisms used for working up fabrics of very little tensile strength.

The spinning process is favorably influenced 25 by copiously moistening the longitudinally cut tobacco strips, before they are worked up. A moistening liquid of 50% of glycerine and 50% of water has been found very efficient. For an equable moistening it is preferable to season the 30 tobacco fibres in their moistened condition.

From the ready spun tobacco threads a fabric of tobacco may be woven which is wrapped about the filling of the cigarette, or the tobacco threads may be wound directly round the filling of the 35 cigarette in the same well known way as textile threads are woven round the cables for conducting electricity.

After having been provided with its tobacco

wrapper the cigarette may be pressed for flattening the same. By compressing the wrapper its sealing property is augmented.

It is already known to make cigarettes with 60 wrappers of tobacco. But according to the known method wrappers are employed which consist of one single piece of a tobacco leaf. For this reason the cigarettes made according to the known method have not the good mechanical 65 properties of an ordinary cigarette.

In the annexed drawing,

Figure 1 is a view of a cigarette made according to the invention, the wrapper consisting of threads coiled around the filler.

Figure 2 is an enlarged longitudinal section 70 of a portion of the same.

Figure 3 is a view of a cigarette having a woven wrapper.

Figure 4 is an enlarged cross section of the 75 cigarette shown in Figure 3.

In Figures 1 and 2, the numeral 1 designates the filler of the usual type, and 2 designates the tobacco threads wrapped directly around the filler.

In Figures 3 and 4, 3 designates the usual filler 80 and 4 designates the tobacco threads woven into a fabric which is wrapped around the filler. In both forms, the cigarette is shown as before being subjected to compression.

I claim:

1. A cigarette comprising a filler, and a wrapper consisting of spun tobacco threads wrapped around the filler.

2. A cigarette comprising a filler, and a wrapper consisting of tobacco threads woven together 90 and enclosing the filler.

WILHELM ZIEHE.
